UNITED STATES PATENT OFFICE.

THEODORE MINER, OF BROOKLYN, NEW YORK.

DESIGN FOR GAME-COUNTERS.

Specification forming part of Design No. **11,302**, dated July 22, 1879; application filed June 17, 1879.
[Term of patent 3½ years.]

To all whom it may concern:

Be it known that I, THEODORE MINER, of the city of Brooklyn, in the county of Kings and State of New York, have originated and designed a Pattern for a Game-Keeper, of which the following is a full and clear description, reference being had to the accompanying drawing, making a part of this specification.

This invention has for its object the ornamental construction of a small machine or device for keeping the accounts or points made by contestants in any game, such as cards, checkers, &c.

The machine or device itself consists of a base-plate or rest, A, in the center of which rises a vertical stem, B, to which is attached a finger or pointer, C, the said finger or pointer being directed by the rotating stem, to which it is attached, to one of a series of figures surrounding the said stem in an annular field concentric with the rotating stem B.

The base-plate or rest A has a flat, or nearly flat, top face, a, circular in plan, and through the center of which rises the vertical stem B, the particular mechanism of which need not be herein particularly described. Arranged around the periphery of the face a is an annular field, a¹, in which are concentrically arranged the figures a², that indicate numerically the points made in the game by reason of the finger or pointer C being directed thereto as may be desired. Surrounding the outer edge of this field a¹ is an ornamental circular bor-

der, a³, below which a curved or vertical line, a⁴, extends a short distance and connects with a convex field, a⁵, which extends outward and downward to the base or annular rim a⁶, on which the whole machine rests. The top edge of the base-rim is enriched with a row of ornamentation, a⁷, and the convex field a⁵ has a line of running ornament or foliation, a⁸, extending quite around the base-plate A. The top end of the central stem, B, terminates in a foliated ornamentation, b, and the outer end of the pointer C is ornamentally constructed at c, so as to reduce it symmetrically to an acute point.

The annular row of ornamentation a⁷ near the base of the stand, and the annular row of ornamentation a³ on the top face of the stand, consist of hemispherical raised work, and the ornaments a⁵ consist of pointed foliations in half-relief, while the ornamentation b on top of the stem B is simply fretted work with very slight relief.

Having described my invention, I claim—

The game-keeper having a base, A, and stem B, ornamented respectively with hemispherical work a³ and a⁷, and the pointed foliation a⁵ and the fretted leaves b, substantially as described and set forth.

THEODORE MINER.
